UNITED STATES PATENT OFFICE

OSCAR CHARLES ROESEN, OF BROOKLYN, NEW YORK, ASSIGNOR TO WOOD NEWSPAPER MACHINERY CORPORATION, OF NEW YORK, N. Y., A CORPORATION OF VIRGINIA

INTAGLIO PRINTING PRESS

Application filed November 10, 1927, Serial No. 232,308. Renewed June 11, 1930.

The principal objects of this invention are to provide means for eliminating the lack of register between the first and second impression cylinders of an intaglio printing press due to the shrinking of the web after the first impression and to provide for shrinking the paper before it is sent through the first pair of printing cylinders so that both the first and second printing cylinders 10 may be made of the same diameter, thereby eliminating the necessity for estimating the amount of shrinkage and making the cylinders different sizes to accommodate that shrink.

Other objects and advantages of the invention will appear hereinafter.

Reference is to be had to the accompanying drawings, in which

The figure is a diagrammatic view of an intaglio printing press illustrating a preferred embodiment of this invention.

In the intaglio printing process it is necessary to dry the ink on the paper immediately after each impression. This is generally done by passing the web around heated drums which revolve at the speed of the web and dry the latter while it is in contact therewith. This has a tendency to shrink the web while passing between the first and the second impression cylinders as well as between the second impression cylinder and the folder. This causes a considerable lack of register between the first and second impression cylinders, as the length 30 of a paper is considerably shorter before entering the second impression cylinder, than it is after leaving the first impression cylinder.

To compensate for this, it has been the trade custom to reduce the diameter of the second impression cylinder over that of the first, the amount of the reduction being proportional to the shrinkage produced by the heating action of the drums. This, of course, is merely a compromise, as it is difficult to predetermine the amount of shrink which is produced under varying atmospheric conditions and is therefore the cause of considerable annoyance to the printer. It is my purpose to shrink the paper before it

is sent through the first pair of printing cylinders, so that both the impression cylinders may be made of the same diameter and thereby take the guesswork out of the registering of the first with the second impression. 55

I accomplish this by passing the web W from the paper roll R over a heated drum D before it enters the first printing couple consisting of the impression cylinder I and the printing cylinder P. This heated drum 60 may be a hollow drum, heated by steam or other means and it dries the paper before it is inked. The result is that the web is thoroughly dried before it receives the impression and there is no tendency to 65 shrink the web while passing between the first and second impression cylinders.

Also to keep the web in the same condition while passing to the second impression cylinder and to the folder I provide a drum 70 D¹ for heating and drying the web after its first impression and before its second impression, also to keep the condition of the web constant as to dryness, I pass it over a third heating drum D² when it leaves the 75 second printing couple and before it passes to the folder.

I also prefer to moisten the web as it passes from the web roll to the first drying drum in order to make the drying process 80 more effective to secure uniform shrinkage. For this purpose I provide water fountains F and rolls B for applying moisture to both sides of the web just before it reaches the first drying drum D. 85

In this way the shrinkage of the web while passing from one printing point to the next and from the last printing point to the folder is done away with and reduction in the diameter of the second impression cylinder, which has been necessary heretofore on account of the shrinking, is also eliminated. The two impressions register with each other and the web, when it reaches the folder, is at a constant and proper length 90 because shrinkage has been taken care of before it reaches the folder. This enables me to provide an intaglio print with a printing couple having the proper diameters of cylinders and enables me to provide the 95 100

impressions in exactly the right place and the folds at the proper distances apart along the web.

Although I have illustrated and described only one form of the invention I am aware of the fact that modifications can be made therein by any person skilled in the art without departing from the scope of the invention as expressed in the claims. Therefore, I do not wish to be limited in these respects, but what I do claim is:

1. In an intaglio printing machine, the combination with two printing couples, of means for drying the web to shrink it thoroughly before it passes through the first printing couple, and means for moistening the web just before it is thus first dried.

2. In an intaglio printing machine the combination with two printing couples of means for drying the web to shrink it thoroughly before it passes through the first printing couple, means for moistening the web just before it is thus first dried, means for drying the web in its course between the first printing couple, and the second printing couple, and means for drying the web after it passes the second printing couple and before it passes to the folder.

In testimony whereof I have hereunto affixed my signature.

OSCAR CHARLES ROESEN.
